INVENTOR

UNITED STATES PATENT OFFICE.

MILES HASTINGS, OF BELOIT, WISCONSIN.

LAWN-MOWER SHARPENER.

1,263,666.

Specification of Letters Patent. Patented Apr. 23, 1918.

Application filed May 3, 1917. Serial No. 166,203.

To all whom it may concern:

Be it known that I, MILES HASTINGS, a citizen of the United States, residing at Beloit, in the county of Rock and State of Wisconsin, have invented a new and useful 5 Lawn-Mower Sharpener, of which the following is a specification.

The present invention relates to a sharpener, particularly adapted for sharpening 10 the blades of lawn-mowers, and other tools or implements, and has for an object to provide a device which may be held in the hand and applied to the blade of the lawn-mower, and which securely holds a file, or other suitable 15 abrasive tool, for grinding the blade.

The present invention provides a sharpener to be held in the hand, which has a one-piece body portion, is provided with a flat, straight guide to accommodate knives of 20 spiral, straight, or other form, and which is provided with means for protecting the edge of the knife as the same is being sharpened.

The invention will be best understood from a consideration of the following detailed description, taken in connection with the accompanying drawings, forming part of this specification, with the further understanding that while the drawing shows a practical form of the invention, the latter is 25 not confined to strict conformity with the showing of the drawing, but may be changed and modified, so long as such changes and modifications come within the scope of the appended claims.

35 In the drawing:—

Figure 1 is a perspective view of a lawn-mower sharpener, constructed according to this invention.

Fig. 2 is a transverse section, taken 40 through the same, the dotted lines showing a lawn-mower blade as applied to the sharpener.

Fig. 3 is an edge view of the sharpener, showing the abrasive tool in place.

45 Fig. 4 is a detail perspective view of the file or abrasive tool.

Fig. 5 is a fragmentary, enlarged sectional view, showing the rounded retaining shoulder and the position of the abrasive tool, 50 which is held against the shoulder, the view bringing out more clearly the recess for the protection of the cutting edge of the blade.

Referring to the drawing, 10 designates a handle of suitable size and configuration to 55 fit in the hand, and is provided upon one side with a relatively flat shank 11. The shank

11 has, in its outer edge, a longitudinal recess or slot 12, providing at one side of the shank a short lip 13, and at the other side of the shank a long lip 14. The long lip has an inclined inner wall 15 terminating at its outer end in a stop or retaining shoulder 16. 60

A file, or other suitable abrasive tool 17, preferably rectangular in cross section, is fitted in the slot 12 behind the shoulder 16, 65 and is held against the shoulder and the inclined wall 15, by clamping screws 18, or the like. The screws 18 pass through the short lip 13 and bind against the adjacent side of the tool 17. 70

As shown to advantage in Fig. 5, the shoulder 16 is provided with a rounded edge, which flares outwardly away from the adjacent face of the tool 17 to provide, between the shoulder and the tool, a groove or recess 75 19 to accommodate the sharp edge of the blade 20, when the sharpener is placed against the latter.

Beyond the shoulder 16, the long lip 14 has a flat straight face 21 constituting a 80 guide extending the full length of the shank 11, and adapted to support the blade 20 in position against the file 17. The short lip 13 terminates substantially in the plane of the outer face of the tool 17, so that when a 85 curved or spiral blade is employed, the blade will not bind between the lips 13 and 14, but may be held in place by contact against the single guide 21.

In the case of a curved or spiral blade, the 90 blade makes contact with the guide 21 at the ends of the latter only, thus reducing friction to a minimum, and holding the blade in proper position against the file 17. When the blade is in position, the abrupt or 95 cutting edge 22 extends into the groove or recess 19, and is not dulled by wiping contact against any part of the holder, or body, of the device.

The inner wall 15 is inclined at an angle 100 of substantially ten degrees to the guiding face 21, and when the tool 17 is clamped in position, the same being rectangular in cross section, its outer face is presented at an angle of substantially ten degrees from the perpendicular with respect to the guiding face 21 which insures the proper bevel being given to the blade. Thus, when the cutting blade 20 is fitted against the guide 21, its beveled edge rests flat against the file 17. 110

What is claimed is:—

1. A sharpener comprising a holder hav-

ing a slot in one edge, and long and short lips at the opposite sides of the slot, said long lip having an inclined inner wall terminating substantially opposite to the end 5 of the short lip in a retaining shoulder, and having a straight guiding face beyond said shoulder, a rectangular tool fitting in said slot upon said shoulder, and clamping means carried by the short lip and engaging 10 the tool to bind the same against said inclined wall and shoulder for holding the tool at an angle to said guiding face, said shoulder having a rounded edge flaring away from the adjacent face of the tool and 15 providing therebetween a groove adapted to receive the cutting edge of a blade when the tool is applied thereto.

2. A sharpener comprising a holder having a slot in one edge, and long and short 20 lips at opposite sides of the slot, said long lip having an inclined inner wall terminating substantially opposite to the end of the

short lip in a retaining shoulder and having a straight guiding face beyond said shoulder, a rectangular tool fitting in said slot 25 upon said shoulder, and a screw carried by the short lip and directly engaging that face of the tool opposite the face which is in engagement with the inclined wall of the long lip to bind said tool against 30 said wall and shoulder for holding the tool at an angle to said guiding face, the tool being of a size in cross section less than the space between the inner walls of the long and short lips for the ready introduction of 35 the tool in the slot.

In testimony, that I claim the foregoing as my own, I have hereto affixed my signature in the presence of two witnesses.

MILES HASTINGS.
